UNITED STATES PATENT OFFICE.

ADAM H. PRENZEL, OF HALIFAX, PENNSYLVANIA, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE.

1,278,503.

Specification of Letters Patent. Patented Sept. 10, 1918.

Application filed June 14, 1913. Serial No. 773,752.

To all whom it may concern:

Be it known that I, ADAM H. PRENZEL, a citizen of the United States, residing at Halifax, in the county of Dauphin and State of Pennsylvania, have invented certain new and useful Improvements in Shoes, of which the following is a specification, reference being had therein to the accompanying drawing.

10 This invention relates to improvements in shoes.

The present invention aims to provide a shoe which can be manufactured very economically but which will be strong and durable, which will compare favorably in appearance with more expensive shoes of the well-known welted and turned types, and which will retain its shape and good appearance even after long wear.

20 In the embodiment of the invention herein disclosed by way of illustration, the shoe upper lining is stitched to the insole independently of the upper, the lasted upper is stitched while under tension to the insole independently of the attachment of the outer sole, and the outsole is independently secured to the upper, lining, and insole, making possible substantial economies of manufacture while providing great strength and 30 durability of shoe construction.

Other objects and advantages of the invention will be apparent from the description of the construction shown in the accompanying drawings, but the embodiment herein shown and described may be modified or changed within the spirit and scope of the invention and within the scope of the appended claims.

In the drawings,

40 Figures 1, 2 and 3 represent respectively a bottom plan, a longitudinal, and a cross section of an inner sole used in the manufacture of the shoe.

Fig. 4 is a side elevation of the shoe partially completed showing the lining portion properly lasted.

45 Fig. 5 is a similar view showing the upper lasted to the inner sole and lining.

Fig. 6 is a cross section showing the first step in the manufacture of the shoe, wherein 50 the lining is lasted and secured in place.

Fig. 7 is a similar view showing the parts with the upper applied.

Fig. 8 is an enlarged section through the finished seam.

Fig. 9 is a longitudinal section through a slightly modified form of inner sole.

Fig. 10 is a cross section of the same.

Fig. 11 is a cross section through the shoe and last, and

Fig. 12 is an enlarged detail section of the same in the modified form.

In the drawings, the last is designated by the letter A, B the inner sole, and C the outer sole. In the preferred embodiment of the 65 invention the inner sole is provided along the outer edge of the shank and fore part with a flexible tape D constituting a flexible lining and upper securing member. The width of this tape when pressed down parallel with the inner sole is such as to extend outwardly beyond the edge of the inner sole, as clearly shown in Fig. 8. This tape or flexible projecting member is conveniently secured to the inner sole below the upper 70 marginal portion thereof by a line of stitches e. E represents the lining which is stretched over the last A, tightly drawn down around the sides of the last, and secured by a series of stitches d to the middle portion of the 75 tape D. The lining being properly lasted and secured in position to conform to the shape of the finished article, the upper F is properly lasted and stretched around the last over the lining, its free edge f being 80 secured fixedly while under tension by a line of stitches f' to the projecting edges of the 85 lining and tape, the stitches being positioned in close proximity to the stitches e of the lining and tape. In this condition, the shoe 90 is ready to receive the outer sole. The outer sole C is conveniently of uniform thickness throughout and is of a width so as to extend somewhat beyond the plane of the side of the shoe, as is usual.

In the drawing, the sole is shown some-

what depressed at the point of union, it being understood that the invention is one wherein it is not necessary to cut out or remove any portion of the outer sole. In applying the outer sole, the same is placed against the bottom of the last with the inner sole interposed, the outwardly projecting portions of the tape, lining and edge portion of the upper being arranged on the upper outer edge of the outer sole. While in this position, a suitable welt G may be applied and the five superposed layers C, D, E, F, G are then secured together by a row or rows of stitches g. The welt G may be carried well under the overhanging part of the upper, as shown in Fig. 8. The heel part of the shoe may be constructed in any well known manner. In the construction of the shoe above described, it will be observed that the lining having been properly lasted and secured to the inner sole provides a smooth surface over which the upper may be drawn. Also, by attaching the upper both to the lining and to the flexible tape or flap of the inner sole, a firm anchorage is secured between the upper and the inner sole reinforced by the edge portion of the lining. By extending the tape and lining so as to underlie the edges of the upper at the point of connection with the outer sole, a very secure and strong anchorage and union is effected through the stitches which pass through all of the parts.

In the modification shown in Figs. 9, 10, 11 and 12, the parts are arranged in a manner similar to the other form, except that in lieu of the separate tape strip or flap, a thin lip H is formed on the edge of the inner sole, and through this lip the line of stitches h is passed, connecting the same with the lining. The upper is drawn down and connected by a line of stitches h' to the edges of the lining and the lip or flap H. In uniting the parts, a row of inclined stitches K may be employed passing through the flexible lip H, the edge of the lining, and the edge of the upper.

It should be understood that while the invention contemplates a sole preferably of uniform thickness, thus avoiding cutting or skiving off the outer edge of the sole, it is appreciated that in some cases it may be found expedient to reduce the thickness of the edge, although ordinarily the added step and consequent expense will not be found to be necessary or warranted. An important advantage resulting from stitching the edge of the upper in beyond the edge of the inner sole and securing it in this lasted position is that the pressure of the foot within the shoe is resisted, first, by the lining and its attachment to the inner sole, second, by the upper and its attachment to

the inner sole permanently and below a marginal portion of the innersole, and third, by the attachment of the lining, upper and innersole to the outer sole. The shoe thus described can be made to compete successfully with turned or welted shoes by reason of economy of manufacture, strength, durability, and attractive appearance.

The process of shoe making herein disclosed is not herein claimed but constitutes the subject matter of a copending application Serial No. 773,753, filed June 14, 1913, 75 upon which was granted United States Letters Patent No. 1,181,732, dated March 16, 1915.

Having thus described the invention, what is claimed as new and desired to be secured by Letters Patent is:

1. A shoe comprising an inner sole, a lining, means for securing the lining adjacent to its edge to the innersole beneath a marginal portion of the latter, an upper, means 85 for securing the edge portions of the upper to the lining and to the inner sole beneath said marginal portion, said means for securing the upper to the inner sole and lining being independent of the attachment of the outer sole, an outer sole, and means for securing the outer sole to the inner sole, lining and edge of the upper.

2. In a shoe, the combination with an inner sole having a flexible tape secured to its under face and extending beyond its edge, of a lining extending over the edge of the inner sole and secured to said tape adjacent to the inner sole, an upper projecting over the lining and having its edge 100 secured to the tape and to the lining by a line of stitches adjacent to the line where the lining is secured to the tape, an outer sole, and another line of stitches for securing the outer sole to the upper, lining and 105 tape.

3. In a shoe, the combination with an inner sole having a relatively flexible marginal lip below the marginal portion of the body of the innersole, of a lining having its edges 110 secured to said flexible lip, an upper secured to the lining by a line of stitches, an outer sole, and another line of stitches for securing together the outer sole, lining and upper.

4. A shoe comprising an inner sole having a relatively thin and flexible marginal flap portion, a lining stitched adjacent to its edge to said flap portion, an upper secured adjacent to its edge to said flexible 120 portion and lining independently of the outer sole attachment, an outer sole, and means constituting the sole means of attachment for securing the outer sole, flexible portion and upper together.

5. A shoe comprising an inner sole hav-

ing a flexible part attached thereto and extending outwardly therefrom, a lining secured to said flexible part, an upper, means for securing the upper to the inner sole independently of the outer sole attachment, an outer sole, a welt, and means independent of the first mentioned means for securing the welt, upper, lining, flexible portion

and outer sole together, substantially as described.

In testimony whereof I affix my signature in presence of two witnesses.

ADAM H. PRENZEL.
